UNITED STATES PATENT OFFICE.

ALTER L. SCHWARTZBERG, OF SHREVEPORT, LOUISIANA.

VENTILATOR.

Application filed October 30, 1925. Serial No. 65,871.

This invention relates to improvements in ventilating apparatus for building structures, and has for its prime object to provide a ventilator which may be readily mounted 5 in the walls of a building so as to provide a suitable circulation of air at all times.

A further object of the invention is the provision of a ventilating apparatus adapted to be mounted in elevated position so that 10 the air in the upper portion of a room may freely circulate.

A still further object of the invention is the provision of a ventilator of compact and durable structure designed to be conveniently positioned in a dwelling and capable 15 of being manufactured at a comparatively reasonable cost.

Other objects and advantages of the invention will become apparent as the description progresses.

In the accompanying drawing forming a part of this specification and in which like numerals are employed to designate corresponding parts throughout the same:

25 Figure 1 is a fragmentary side elevation of a building showing my improved ventilating structure mounted thereon.

Figure 2 is an enlarged transverse sectional view through a section of a building 30 wall and ventilator constructed in accordance with my invention and taken substantially upon the line 2—2 of Figure 1.

Figure 3 is a perspective view in separated position, of my improved ventilator.

35 In the drawing, wherein for the purpose of illustration is shown the preferred embodiment of my invention, the numeral 5 generally indicates the side walls of a conventional type of building equipped with a common type of window 6. This building is a simulation of a dwelling and, as is well known, the window 6 is situated in a position intermediate the floor and ceiling of a room therein. While it is customary to build the window adjacent the ceiling of the room, in many cases the upper end of the window is a substantial distance below the ceiling so that the upper strata of air remains practically immovable. My invention 40 contemplates the use of ventilating structures to be mounted in the building walls above the window, as apparent from Figure 1 of the drawing. The provision of this structure will necessarily cause the air 45 in the upper portion of a room to circulate,

so that the heated foul air may escape from the room and fresh air enter.

Referring now more particularly to the structure embodying my invention, the numeral 7 designates in its entirety a box like body or casing of generally rectangular formation composed of a top 8, bottom 9, and end members 10. This body as shown in Figures 2 and 3 of the drawing, is preferably constructed of wood or similar material, 50 the width thereof being arranged to conform to the width of the building wall. The casing 7 is to be mounted preferably in a longitudinal position in a suitable opening formed in the building wall, the opening being 55 formed of exact size so that the casing may be snugly positioned therein.

From the foregoing description and drawing, it is apparent that the sides of the casing are open this being arranged so as to accommodate detachable side members 12. These members are constructed of rectangular formation somewhat larger than the contour of the casing so as to over-hang the casing structure. Each of the side members is 60 formed with a rectangular frame embodying longitudinal side beams 13 beveled or rounded at their outer portions provided at the center and ends with grooves. Extending between the longitudinal beams 13 65 and connecting therewith are transverse beams 14 of somewhat shorter construction, the extremities of these transverse beams being provided with tongues engageable with the grooves formed in the side beams. While 70 I have shown and described a tongue and groove connection between these members, the structure is not restricted to this particular form of connection, and any desirable connecting means may be employed. Extending between the longitudinal beams 75 13 and connected to the centers thereof by a tongue and groove connection is a central brace bar 15. This bar supports the interior 80 extremities of a plurality of longitudinal bars 16 arranged in spaced intervals and extending between the central bar 15 and the transverse end beams 14, the ends of the longitudinal bars 16 being secured to the vertical beams in any suitable manner. It 85 is evident, that the side members 12 will be provided with a plurality of longitudinal rectangular formed openings through which the air may readily pass from the exterior 90 to the interior of a building. Each venti- 95 100 105 110

lator embodies two of these detachable side members, the exterior member being secured by nailing or similar manner while the interior side member may be securely positioned by screws or the like. The enlarged construction of the apertured side members will cause these members to fit tightly against the wall of the building so as to prevent the formation of enlarged crevices so that rain or other matter may enter the dwelling.

It is to be understood that the form of my invention herewith shown and described is to be taken as the preferred example of the same and that various changes as to the size, shape and arrangements of parts may be resorted to without departing from the spirit of the invention or the scope of the subjoined claim.

Having thus described my invention, I claim:

A ventilator structure of the character described, comprising a rectangular casing body open at opposite sides and designed for insertion in a building wall, a grating designed to be secured over each open side of said casing and comprising a frame of greater over-all length and width than the casing and of substantially the same interior width and length as the same, said grating frames abutting against the wall faces to secure the structure in position in the wall, longitudinally extending and transverse bars in each of said grating frames, and means for securing said grating frames to the box structure.

In testimony whereof I affix my signature.
ALTER L. SCHWARTZBERG.
